Inventor.

Erlich Schinscholl,
by A. T. Neelco,
his Attorney.

UNITED STATES PATENT OFFICE.

ERICH SCHINSCHOLL, OF CINCINNATI, OHIO.

ENVELOPE CLASP.

Application filed August 31, 1922. Serial No. 585,419.

To all whom it may concern:

Be it known that I, ERICH SCHINSCHOLL, a citizen of the United States, residing at Cincinnati, in the county of Hamilton and 5 State of Ohio, have invented certain new and useful Improvements in Envelope Clasps, of which the following is a specification.

It is the object of my invention to provide 10 a new and improved envelope clasp whereby an envelope may be readily closed or opened and so constructed that little thickness is added to the envelope at the clasp; further, to provide envelopes with clasps which will 15 not detrimentally interfere with the sliding of the envelopes one upon the other or with the stacking of the same; and further, to provide a clasp for an envelope which is simple in construction, is easily applied to 20 the envelope, provides a secure closing means for the envelope, and is readily released to open the envelope when desired.

The invention will be further readily understood from the following description 25 and claims, and from the drawings, in which latter:

Fig. 1 represents a plan view of an envelope, partly broken away, having my improved clasp applied thereto.

Fig. 2 is an enlarged view of my improved device.

Fig. 3 is an inside elevation of the same.

Fig. 4 is a central longitudinal section of the same, taken on the line 4—4 of 35 Fig. 2.

Fig. 5 is a perspective view of the latch member of my improved device; and

Fig. 6 is a perspective view of the keeper member of my improved device.

The envelope is indicated at 11. It is shown partly broken away. It may be of any suitable size, shape and material. It comprises a body 12 and a flap 13. It may be formed out of a single piece of paper, 40 and have a middle lap 14, the edges of the blank out of which the envelope is formed being lapped and pasted to form the lap 14.

The clasp is exemplified as comprising a latch member 16 and a keeper member 17.

Each of these members is formed out of a thin sheet plate, preferably of metal.

The latch member is formed with a suitable head 21 from which attaching prongs 22 extend, the prongs piercing the material 55 of the flap 13 and preferably also piercing

a reinforce piece 23 of paper pasted to the flap. The prongs are bent toward the head for clamping the material of the flap and the reinforce piece between the rear face of said head and the prongs. A shank 24 extends from the head. A tongue 25 extends from the shank. Shoulders 26 are formed at the base of the tongue.

The outer end of the tongue has a retaining lug 28 formed up therein, preferably by striking down the metal of said lug from the body of said tongue with a sharp edge 29 to form a shoulder presented toward the base of the tongue and providing the outer end of the lug with a slanting face 30 upon which the end of the tongue readily rides on the keeper member when closing the envelope. The tongue is preferably somewhat resilient.

The keeper member is formed with attaching prongs 31, the prongs piercing the lap 14, and being bent toward the body of the keeper member for clamping the material of said lap between the prongs and said body.

The body of the keeper member has a cross-web 33 formed up therefrom, which is preferably raised above the upper or tongue-contacting surface of said body a distance substantially equal to the thickness 85 of the tongue, so as to hold the tongue toward the keeper member when the tongue is inserted under said cross-web.

The keeper member is provided with slots 34, 35, at the respective sides of the cross-web, the tongue being received through said slots. These slots are preferably enlarged into the form of openings to permit the ready passing of the free end of the tongue having the retaining lug thereon through 90 said slots and under said cross-web and past the outer wall 36 of the slot 35, the slanting face 30 of the retaining lug aiding in said closing movement of the tongue.

When the clasp is closed the shoulders engage the outer upturned ends of the cross-web and the shoulder 29 of the retaining lug engages the lower edge 36 of the keeper member for holding the clasp in clasped relation, the tongue being slightly resilient 105 and the cross-web 33 holding the tongue toward the keeper member. The shoulders 26 limit the inward movement of the tongue. When the shoulders 26 engage the cross-web, the flap 13 will be parallel with the body of 110

the envelope and the envelope be closed, with the shoulder 29 in engagement with the edge 36 of the keeper member.

- In order to open the envelope it is only necessary to raise the outer end of the tongue to release the retaining lug, whereupon the tongue may be readily slipped endwise out of the keeper member. The release of the tongue may be readily effected for instance by engagement of the cross-web by the nail of the first finger and the engagement of the outer edge of the tongue by the thumbnail, and the pressing of said nails toward each other.
- 15 My improved device is economically made and provides means whereby the envelope may be repeatedly closed and opened or repeatedly used.

Having thus fully described my invention, 20 what I claim as new, and desire to secure by Letters Patent, is:

1. An envelope clasp comprising a latch member and a keeper member, said latch member comprising a tongue, said keeper member comprising a thin sheet plate having a cross-web struck up therefrom to form a slot at each side of said cross-web, said tongue received upon said plate through said slots, said cross-web raised above the tongue-contacting surface of said plate substantially the thickness of said tongue to hold said tongue toward said plate, said tongue provided with an inwardly bent retaining lug, said plate provided with a shoulder contacted by said retaining lug, and said retaining lug and said shoulder distanced from said cross-web a distance to permit flexing of said tongue away from said plate to release said retaining lug from said shoulder, and means whereby to fix said members respectively to the flap and the body of an envelope.

2. An envelope clasp comprising a latch member and a keeper member, said latch member comprising a thin sheet plate formed with a tongue and a pair of shoulders at the base of said tongue, said tongue provided with an inwardly bent retaining

lug at its outer end, said keeper member comprising a thin sheet plate having a cross-web struck up therefrom to form a slot at each side of said cross-web, said tongue received upon said second-named plate through said slots with said shoulders contacting a wall of one of said slots and said retaining lug contacting an edge of said keeper member distanced from said cross-web to permit flexing of said tongue away from said keeper member to release said retaining lug from said edge, and said cross-web raised above the tongue-contacting surface of said second-named plate substantially the thickness of said tongue to hold said tongue toward said second-named plate, and means whereby to fix said members respectively to the flap and the body of an envelope.

3. An envelope clasp comprising a latch member and a keeper member, said latch member comprising a thin sheet plate formed with a tongue at one end and with attaching prongs at its other end, said keeper member comprising a thin sheet plate having a cross-web struck up therefrom beyond one face of said second-named plate to form a slot at each side of said cross-web and having attaching prongs struck up therefrom at its other face, said tongue received through said slots, the outer end of said tongue and said second-named plate provided with a retaining lug and an edge 75 coacting therewith distanced from said cross-web to permit flexing of the outer end of said tongue away from said second-named plate to releasably latch said tongue and said second-named plate together, and said members fixed by means of said prongs respectively to the flap and the body of an envelope.

In testimony whereof, I have hereunto signed my name in the presence of two subscribing witnesses.

ERICH SCHINSCHOLL.

Witnesses:

JOSEPH LEMKUHL,
DELMA WERNING.
